Primary Examiner — Michael A. Pratt*(74) Attorney, Agent, or Firm* — Woodard, Emhardt, Henry, Reeves & Wagner, LLP(57) **CLAIM**

The ornamental design for a pistol as shown and described.

DESCRIPTION

FIG. 1 is a front perspective view of the pistol showing a first embodiment of our new design;

FIG. 2 is a back perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a back view thereof.

The evenly broken lines disclose unclaimed portions of the pistol and magazine, and the dash-dot broken lines depict unclaimed boundaries of the claimed design. The broken lines form no part of the claimed design.
